AUTOMATIC VOLUME CONTROL

Karl Wilhelm, Berlin-Charlottenburg, Germany,
assignor to Siemens & Halske Aktiengesellschaft, Siemensstadt, near Berlin, Germany, a corporation of Germany

Application July 2, 1932, Serial No. 620,559
In Germany September 5, 1931

8 Claims. (Cl. 250—20)

The present invention relates to circuit arrangements for automatic amplitude regulation in signal transmitter systems.

Because of fading phenomena which are observed in the reception of long distance wireless transmitter systems or stations, and which are liable to seriously disturb reproduction or signal reading while all other conditions may be perfect, recourse has been had to automatic amplitude regulators which usually operate by keeping at a constant value the carrier wave potential across the demodulator. In practicing such a regulation method it would seem most advantageous from a practical viewpoint to alter the radio frequency amplification by varying the biasing grid potential of the radio frequency amplifier tubes, and to use as the control voltage the plate direct current potential of the demodulator, this being a function of the radio frequency potential to be demodulated.

The change in the plate potential of the demodulator, however, in the majority of cases is too small to be directly usable for the regulation of the gain to an extent made necessary by the fluctuations of volume level. Hence, the necessity to amplify the control potential derived from the demodulator before the same is fed to the amplifier to be regulated. It is known in the prior art to use for this amplification of the control potential a distinct tube which, since very slow potential variations are dealt with, is most suitably of the direct current amplifier type. However, the use of such a separate tube especially where relatively small receiver stations are concerned, such as broadcast receivers for which the cost is of decisive importance, means an inadmissible extra expense.

Now, according to the present invention this difficulty is obviated by that the amplification of the direct current control potential is effected in one or more amplifiers provided for the amplification of the incoming signal. Fundamentally speaking, any desired amplifier, say, a radio frequency amplifier, and intermediate frequency amplifier, or else an audio frequency amplifier, or any desired combination thereof, or else a rectifying amplifier could be used therefor. Also the gain variation serving for amplitude regulation may be effected at any suitable point. As a general rule, however, it is of advantage that the point at which the amplitude regulation of the signal currents occurs should be located ahead of, or below, the signal current amplifier or amplifiers insuring the direct current amplification of the control potential. Using this fundamental

rule in connection with receiver apparatus comprising a plurality of radio frequency amplification stages, this means that in one or more of the initial radio frequency stages there occurs the amplitude regulation of the signal current, and in one or more of the subsequent radio frequency stages the direct current amplification of the control potential.

The drawing shows an embodiment of the invention as incorporated in a three circuit receiver usable for broadcast reception and comprising a two-stage radio frequency amplification. The incoming radio frequency potential is fed by way of the first tuning circuit S1, included in the aerial circuit, to the first radio frequency tube V1 which, for instance, may be of the screen grid type.

The plate circuit of this tube V1, in well known manner, is coupled, by way of a stopper circuit S2, with the grid circuit of a second radio frequency tube V2 which likewise may be of the screen grid type. The plate circuit of this tube is in coupling relationship, by way of a third tuned circuit S3, with the grid circuit, say, of a rectifier tube G connected audion-fashion, and the plate circuit thereof contains the primary winding of a low frequency (audio frequency) transformer T. Across the output terminals A of the latter the audio frequency potential resulting from the demodulation may be collected, and be fed on to other amplifier stages in a way well known in the prior art.

In order to make the over-all gain of the receiver apparatus a function of the incoming radio frequency amplitude, the grid circuit of the radio frequency tube V1 is so connected with the plate circuit of the rectifier tube G that with increasing radio frequency amplitudes, owing to the ensuing change in the mean plate potential of the rectifier, the grid biasing potential of the radio frequency is shifted towards the negative end to a corresponding degree. In this scheme, according to the invention, the second radio frequency amplifier tube V2 serves for the amplification of the direct current potential which is to be fed into the first radio frequency amplifier tube V1 as a variable grid biasing potential. With this end in view the end of the grid leak R2 of the tube V2 turned away from the grid is not connected with a fixed potential, but is connected with a definite point of the plate circuit of the rectifier tube G containing the resistances R4 and R6, the tapping point being here chosen most suitably in such a way that the grid biasing potential of the tube V2 in unexcited state,

i. e., in the absence of reception, is negative in reference to the filament.

Similarly, also, the grid leak resistance R_1 of the first radio frequency tube V_1 is not connected 5 with a fixed potential, but is coupled by way of

a resistance R_5 electrically with the plate circuit of the second radio frequency tube V_2 so that the plate potential of the second radio frequency tube forms at the same time the grid 10 bias of the first radio frequency tube.

In actual operation, as the radio frequency volume level rises, the grid potential of the second radio frequency tube V_2 , as a result of decreasing plate current in the rectifier tube G , 15 is shifted towards the positive end so that the potential acting at the plate of the tube V_2 becomes lower, and thus the grid biasing potential of the first radio frequency tube V_1 becomes shifted towards the negative end. The size of 20 such a shift in the first radio frequency tube is appreciably greater than in the second tube since the latter acts as a direct current amplifier for the control direct current potential.

As long as no radio frequency energy reaches 25 the rectifier the grid potential of the first radio frequency tube V_1 is shifted towards the positive end. There exists a danger of the grid current then initiated causing such a damping in the incoming radio frequency energy that the 30 radio frequency energy reaching the rectifier will be insufficient for the actuation of the regulator. In the grid circuit of the second radio frequency tube V_2 a similar action might arise in the presence of radio frequency amplitudes 35 growing beyond a certain measure. In order to meet this danger, therefore, the grids of the two tubes are blocked in a way as shown in the diagram of connections.

In order that the building of the circuit 40 scheme may be as much simplified as feasible in spite of the inter-dependence of the grid and plate circuits due to the direct current amplification, and so that the filaments may be heatable from a single source, an advisable plan is 45 to employ indirectly heated tubes, at least to use this type for the two radio frequency tubes. The filament or heating circuits H of the three tubes may then be fed either in series or in parallel, say, from the direct current or alternating current network, it being, of course, necessary in this 50 connection to be able to adjust the plate and screen grid potentials in a definite way. For this purpose a common or joint voltage divider resistance (potentiometer) R_7 is most suitably 55 used in a way as shown which is connected with the direct current potential N furnished directly from the direct current network or resulting from rectification of the alternating current furnished from the alternating current network.

The invention is by no means confined to the 60 use in connection with receiver circuits for radio transmission systems. Indeed, it will be found useful for all kinds of signal transmission systems wherein automatic amplitude regulation is 65 accomplished by the aid of a control direct current potential. It is moreover immaterial in so far as the applicability or usefulness of the basic idea of this invention is concerned whether the said control direct current is obtained by the 70 rectification of alternating current potential or whether it consists of a directly obtained direct current potential.

While I have indicated and described one arrangement for carrying my invention into effect, 75 it will be apparent to one skilled in the art that

my invention is by no means limited to the particular organization shown and described, but that many modifications may be made without departing from the scope of my invention as set forth in the appended claims.

What is claimed is:

1. In combination with a radio receiver including at least two cascaded high frequency amplifiers and a following rectifier, means for impressing the direct current component of the rectifier output on an input electrode of the amplifier immediately preceding it, and a direct current connection between the output circuit of the last amplifier and a gain control electrode of the first of said cascaded amplifiers.

2. In combination, a high frequency amplifier whose gain is to be automatically regulated, a second amplifier for amplifying the high frequency output of the first amplifier, a rectifier connected to the second amplifier output, means for impressing the direct current component of the rectifier output on the second amplifier whereby the latter amplifies the said component, and means for applying the amplified component to a gain control electrode of the first amplifier for said gain regulation.

3. In an automatic volume control system for a radio receiver, the latter including a pair of radio amplifiers and a detector all in cascade, a direct current connection between the detector anode circuit and the signal grid circuit of the next preceding amplifier, and a second direct current connection between the anode circuit of the last named amplifier and the signal grid circuit of the first of said pair of amplifiers.

4. In combination in a radio receiver including at least two cascaded radio frequency amplifiers, the first of said amplifiers including a resonant input circuit, a resonant network coupling the anode circuit of the first amplifier with the input electrodes of the second amplifier, a detector stage including a tube having its input electrodes coupled to the anode circuit of said second amplifier, a resonant network connected to the detector input electrodes, a resistor in the anode circuit of said detector, a direct current connection between the control grid of the second amplifier and said resistor, a second resistor in the anode circuit of said second amplifier, and a direct current connection between the control grid of said first amplifier and said second resistor.

5. In combination in a radio receiver including at least two cascaded radio frequency amplifiers, the first of said amplifiers including a resonant input circuit, a resonant network coupling the anode circuit of the first amplifier with the input electrodes of the second amplifier, a detector stage including a tube having its input electrodes coupled to the anode circuit of said second amplifier, a resonant network connected to the detector input electrodes, a resistor in the anode circuit of said detector, a direct current connection between the control grid of the second amplifier and said resistor, a second resistor in the anode circuit of said second amplifier, and a direct current connection between the control grid of said first amplifier and said second resistor, said first direct current connection being adjustably connected to said first resistor.

6. In combination in a radio receiver including at least two cascaded radio frequency amplifiers, the first of said amplifiers including a resonant input circuit, a resonant network coupling the anode circuit of the first amplifier with the input electrodes of the second amplifier, a detector
